Wes 1035 —

Cornelius B. Erwin, of New Britain, Conn.
Letters Patent No. 1035 — dated Aug. 10. 1858.

The schedule referred to in these Letters Patent and making part of the same.

To all whom it may concern:

Be it known that I, Cornelius B. Erwin, of New Britain, in the State of Connecticut, have invented or produced a new and original design for Door Lock Plates, and I do hereby declare that the following is a full, clear, and exact description of the same, reference being had to the accompanying drawing making part of this specification.

My said design for the outer plate of a door lock, termed the Pioneer Lock, represents a western pioneer with his rifle, pack, and dog traveling in a forest.

In the accompanying drawing a represents the outer plate of a door lock cast with the design in relief, representing forest trees b with a man c dressed in the well known costume of a western pioneer carrying a rifle d on his shoulder, and pack e suspended thereto, followed by a dog f.

What I claim as new is the design above described and represented in the accompanying drawing cast in relief on the out-side of a door lock plate.
